UNITED STATES PATENT OFFICE.

WILLIAM H. MULLINS, OF SALEM, OHIO.

DESIGN FOR A LOAF OF BREAD.

SPECIFICATION forming part of Design No. 26,958, dated April 20, 1897.

Application filed March 3, 1897. Serial No. 625,904. Term of patent 14 years.

To all whom it may concern:

Be it known that I, WILLIAM H. MULLINS, a citizen of the United States, residing at Salem, in the county of Columbiana and State of Ohio, have invented and produced a new and original Design for Loaf-Bread, of which the following is a description, due reference being had to the accompanying drawing, forming part of this application, which represents 10 in perspective a cylindrical loaf of bread configured by the characteristic features of my design.

The general purpose of this invention is the production and ornamentation of a loaf of bread or other article of food, having for its 15 leading feature a series of transverse corrugations or projections. More particularly described, the design consists in a cylindrical body A, the opposite ends B B of which are 20 of slightly convex form and the surface of which is ornamented by a series of independent corrugations C, transversely arranged. These corrugations C completely encircle the body A in relatively close parallel planes and extend collectively from one 25 end B of the figure to the other, as shown.

As illustrated, it will be observed that the corrugations C are each of comparatively narrow width and abut one upon the other, also that the loaf is noticeably convex at its ends 30 B B, but it will also be observed that the essential feature of the design resides in the transverse surface corrugations aforesaid, which constitute the spirit of the present invention.

Having thus described my invention, what I claim, and desire to secure by Letters Patent, is—

The design for a loaf of bread or other article of food, substantially as herein shown 40 and described.

In testimony whereof I subscribe my signature in the presence of two witnesses.

WILLIAM H. MULLINS.
